F. A. JIMERSON

REVERSIBLE THROTTLE HANDLE

Filed August 7, 1925

Patented Aug. 3, 1926.

1,594,964

UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

REVERSIBLE THROTTLE HANDLE.

Application filed August 7, 1925. Serial No. 48,869.

This invention relates to fluid actuated rotary tools, such as rotary drills and the like, but more particularly to a reversible throttle handle for machines of this type.

Such rotary tools run at comparatively high speed, and a good example of a tool of the general type to which the reversible throttle handle, forming the subject matter of this invention relates, is disclosed in my copending application Serial No. 567,887, filed, June 13, 1922, for fluid actuated rotary tool showing the general organization of the parts of the tool itself.

In such high speed tools especially the manipulation of the throttle should be positive and certain and the objects of this invention are to provide such certainty of operation and at the same time, if desired, insure the automatic return of the valve to neutral position when the valve is released. In some respects the invention is a modification and improvement of the machine disclosed in my copending application Serial No. 29,060, filed, May 9, 1925.

Further objects will hereinafter appear and the invention is shown in one of its preferred forms in the accompanying drawings in which,

Figure 1 is a longitudinal sectional elevation of a rotary drill having the invention applied thereto, with the throttle valve in the handle closed,

Figure 2 is an enlarged detail transverse sectional view on the line 2-2 of Figure 1 looking in the direction of the arrows, with the throttle valve closed,

Figure 3 is an enlarged detail view partly in longitudinal section of a portion of the throttle handle in a plane at right angles to the plane of the section of Figure 1, with the throttle valve open,

Figure 4 is a detail transverse sectional view taken on the line 4-4 of Figure 1 looking in the direction of the arrows,

Figure 5 is a view of a portion of Figure 3 showing the valve cam in neutral position so that the throttle valve is closed as in Figure 1, and

Figure 6 is an enlarged detail transverse sectional view partly broken away and taken through the reversing valve of the machine on the line 6-6 of Figure 1, looking in the direction of the arrows, with the reversing valve open.

In the drawings, only so much of the de-

tails of the rotary drill are shown as will serve to disclose the present invention relating to the reversible throttle handle. The case, or cylinder casing A, having the removable crank case cover B and the removable gear case or front head C together form the frame of the machine inclosing and supporting the operating parts for imparting rotation to a suitable tool, which may be carried in the socket D provided in the drill spindle E.

The drill is provided with the throttle handle body F and the opposite handle G, and the pressure fluid is supplied to the machine through the handle body F and controlled by the throttle valve L manipulated by improved devices in accordance with this invention, so that the valve, if desired, may always be made to return to neutral position when released. Otherwise the valve is both opened and closed by hand.

The crank shaft H is mounted in the ball bearings J in the case A beneath the crank cover B and adapted to be actuated by a fluid actuated motor of any suitable type, as for instance, a multi-cylinder motor having V-type arrangement of cylinders, two of the cylinders K being indicated in Figure 1 at one side of the machine, and at an angle to the axis, the remaining pair of cylinders not being shown. The pistons O reciprocating in the cylinders are connected by connecting rods P to the crank shaft and the distribution of motive fluid to the cylinders, in this instance, is controlled by a rotary valve Q actuated by suitable gearing from the crank shaft. Suitable ports Q' in the casing for each cylinder are controlled by the appropriate ports and passages in the revolving valve Q, but the details of the passages leading to the cylinders and the details of the cycle of operations in admitting and exhausting pressure fluid to and from the cylinders are not further illustrated as they form no part of the present invention.

The crank shaft H is provided with a pinion R meshing with the gear S on the spindle E and another gear T connected to a gear S drives the valve Q through the agency of the pinion U, so that in the present instance the valve is rotated at half the speed of the crank.

In order to feed the working tool forward, an internal feed screw V is mounted in the case and is provided with an extension W.

upon which is mounted a bearing X. A feed screw Y having a center Z and a hand wheel a, as usual, completes these parts of the machine.

5 The machine is preferably provided with a reversing valve b mounted in the sleeve c in the case A in a convenient position to be operatively connected to be actuated by the reversible throttle handle sleeve d rotatable 10 back and forth to a limited degree on the outside of the handle body F, so that as the throttle valve L opens, the reversing valve b is rotated in one direction or the other from closed position to cause direct or re- 15 verse rotation of the motor.

A housing e embracing the handle body F and covering the valve b and the valve stem f, is secured to the case A by means of the screws g, and protects the operative 20 parts beneath it. In this instance the housing also acts as an abutment for holding the valve against endwise movement in one direction. A toothed sector g' on the valve stem engages a toothed sector g² of a handle cam h. The cam h is in the form of a sleeve movable on the body F and has a slot j in the outer flange j' engaged by the tongue k on the handle sleeve d, so that rotation of the sleeve rotates the valve b. A 25 stop pin o conveniently located in the case A is pressed by a spring p and engages one of the depressions r in the inner flange r' of the handle cam h to hold the valve in one or another of the valve positions, either 30 closed or open. The depressions r and the stop pin o may be omitted, if desired, thus permitting the valve L to be closed automatically by the action of the spring t upon 35 release of the handle sleeve d.

40 The throttle valve L is movable longitudinally in the handle body F and normally forced to its closed position on the seat s by suitable coiled spring t. A slot u at the inner end of the valve stem v engages the 45 cross pin w movable in the slot x in the handle body and having rollers y at each end cooperating with and forming the followers of the handle cam h. This cam h has the angular or V-shaped cam surfaces z so that when the rollers y lie at the apex or bottom of the V-shaped cam opening, the parts are all in neutral position and both the throttle valve L and the reversing valve b are closed as shown in Figure 1 of the 50 drawing. Rotation of the handle sleeve d in one direction or the other causes the rollers y to ride up or outwardly on the cam surfaces z to open the throttle valve, which may be automatically returned to closed or 55 neutral position by the pressure of the spring t when the handle sleeve d is released.

In the operation of the device, let it be assumed that the valves L and b are both closed as shown in Figure 1 and that pressure fluid is to be admitted to the machine

by turning the handle sleeve d clockwise as Figure 1 is viewed from the left, to the position of the parts in Figure 3. In such case the cam surfaces z will have moved the throttle valve L to open position and pressure fluid passes through the open portion of the handle body F and passages 2 in the body to the chamber 3 at the inner end of the handle body, and from thence as indicated in Figure 6, through passage 6 in the case, to and 70 through the bushing e and reversing valve b to the passage 6^a in the case, and through the distributing valve Q to the motor cylinders. The exhaust from the cylinders passes out from the distributing valve Q to the passage 7 in the case and from thence through the reversing valve b to the atmospheric 75 exhaust port 8. Upon reversing the movement of the handle sleeve d, which must first pass through neutral position, the throttle L is closed and then opened again and reversing valve b is reversed, in which case the functions of the passages 6^a and 7 in the case is reversed, and the supply of pressure fluid passes to the distributing valve 90 and motor cylinders through the passage 7, while the passage 6^a becomes an exhaust passage.

I claim:

1. In a fluid actuated rotary drill, the combination with a case and motor, of a handle body, a rotatable handle sleeve, a throttle valve in the handle body, a housing secured to the casing and encircling the handle body, a rotatable reversing valve adjacent the handle body, a stem on said reversing valve and abutting the housing to hold the valve against endwise movement in one direction, a handle cam rotatable on the valve body, and operative connections in the housing for transmitting rotary movement of the handle cam to the reversing valve.

2. In a fluid actuated rotary drill, the combination with a case and motor, of a handle body, a rotatable handle sleeve, a throttle valve in the handle body, a housing secured to the casing and encircling the handle body, a rotatable reversing valve adjacent the handle body, a stem on said reversing valve and abutting the housing to hold the valve against endwise movement in one direction, a handle cam rotatable on the valve body and extending into the housing, a toothed sector integral with the handle cam enclosed by the housing, and a toothed sector on the stem of the valve to engage the toothed sector on the handle cam for transmitting rotary movement of the handle sleeve to the reversing valve.

In testimony whereof I have signed this 125 specification.

FRANCIS A. JIMERSON.
